W. S. NEWMAN

MEANS OF SINGLE ARTICLE DELIVERY FROM CONTAINERS

Filed Nov. 1, 1921.

UNITED STATES PATENT OFFICE.

WILLIAM SYLVESTER NEWMAN, OF ALEXANDRA, VICTORIA, AUSTRALIA.

MEANS OF SINGLE-ARTICLE DELIVERY FROM CONTAINERS.

Application filed November 1, 1921. Serial No. 512,113.

To all whom it may concern:

Be it known that I, WILLIAM SYLVESTER NEWMAN, subject of the King of Great Britain, residing at Alexandra, in the State of Victoria, Commonwealth of Australia, have invented certain new and useful Improvements in Means of Single-Article Delivery from Containers; and I do hereby declare the following to be a full, clear, and exact description of the invention, such as will enable others skilled in the art to which it appertains to make and use the same.

My invention relates to improved mechanism whereby single articles, for example matches, are delivered from containers. The articles will, one at a time, be projected conveniently from the container or box, and be held vertically or obliquely, ready to be grasped and removed.

For brevity I will hereinafter usually refer to articles to be delivered as matches, and to containers as boxes, though the articles and containers will not be in practice limited thereto.

My box can be made portable, but in many cases will be formed for placing on or fixing to a counter, table, wall or other support.

In the accompanying drawings a box illustrating the invention is shown, but the construction shown may be modified while still retaining matter hereinafter claimed.

Figure 1 is a plan of part of the box closed.

Figure 2 is a plan of part of the box with its lid removed, and containing a few matches.

Figure 3 is a side view of part of the box with its lid removed, in section on line 3—3 of Figure 2, and with a slide and its actuator depressed to some extent.

Figure 4 shows a sectional view of the upper part of the box, looking towards a tipping jaw.

Figure 5 is an end view in section on about line 5—5 in Fig. 1.

Figure 6 is a side view of the slide and its actuator.

Figure 7 is an edge view of the slide.

Figure 8 is a view of the slide and its actuator from beneath.

In these drawings A is a box having a chamber B to contain matches C, placed parallel, with their heads C¹ at the same end of the box. In Figure 2 parts of matches are omitted to exhibit the construction clearly.

The chamber base D is sloped towards one side, to which the matches gravitate. F is

a slide at that side, and when the slide is lowered some matches mass themselves above it. Slide lowering is effected by hand operation of an actuator. The slide has a top groove J (a known separating means) in which when the slide is lowered a match enters by gravitation. The slide is some distance inward of a wall shown as box side E, whereby when a plurality of matches becomes located above the lowered slide, one or more matches will, as the slide rises, enter a space or pocket G between wall E and slide F, and will be out of the way. From that pocket they later on reach the slide grooves by gravitation.

H is a slide actuator, connected at H² with the slide, and, in order that it may be pressed by the user, a part H¹ of it projects from the box, this actuator being normally kept raised, by a spring J; depressing it affects the spring which returns the actuator and slide to normal raised position when the pressure is removed. The slide is arranged so that its movement agitates the sloping base D, to ensure that matches gravitate as aforesaid, though they generally descend the slope without agitation. Base D is shown as a movable plate supported by a part A¹ of the box. One or more pins A² in part A¹ project each into a slot D¹ in base D, to keep plate D in working positions.

A projection on slide F is provided to cause the agitation, and is formed conveniently by setting a curved plate F¹ on the slide face. This projection as the slide rises and is depressed, pushes plate D, which yields, but after it has been so pushed returns to normal by reason of a spring K located in the box; this spring is retracted by base D as the latter is pushed upward.

The slide top has an end recess M which is overhung by the end of any match lifted in slide groove L, which is shorter than the match it raises.

In the upward path of the overhanging part of the match is an arresting jaw N¹, on an arm or spring finger N. The jaw thus overhangs the recess M, and as the match rises its overhanging end becomes gripped between the jaw N¹ and slide F, which rises a little farther, and thus causes the match to be upended, so that its stem extends more or less vertically, and its gripped end C² is held in recess M by jaw N¹, which will be somewhat retracted.

J¹ is a removable socket or abutment under spring J.

A^3 is a recess in part A^1 to allow for passage of member F^1 , and A^4 is a recess in the wall of chamber B to receive spring N .

It is not essential that the container have 5 a lid; but a lid as P is useful, and I make it transparent when it is desired to allow the operations to be visible. The lid shown is slotted at P^1 to allow for the upward swing of the gripped match. The lid could 10 be modified in various respects.

Various means are known for operating match raising slides and to use such my construction could be modified.

Means may be provided to temporarily fix 15 the actuator and slide in depressed position, until the said means is released, letting the actuator and slide rise.

The surfaces which grip the article raised by the slide should be shaped and dimensioned according to the contour of the 20 article, that is,—to grip a cigar or cigarette the gripping surfaces would be recessed to suit the circular cross section of the article.

A flat sided match is well gripped between 25 flat surfaces.

I claim:—

1. A device as described comprising a container having a chamber with a reciprocating inclined base, and a slide in the con-

tainer adapted to receive articles from the 30 inclined base and acting to shift the base in one direction.

2. In a container having a chamber for small articles, a reciprocating base moving in an edgewise direction, means to yieldably hold said base in one position, and a slide for ejecting the articles adapted on movement in one direction to shift the base in 35 opposition to said means.

3. In a container having a chamber, a 40 sloping base in the chamber mounted to reciprocate in a path coincident with the plane of the base and the direction of its slope, yieldable means to urge the base downwardly, and a slide in the container having means to 45 shift the base in opposition to said yieldable means.

4. In a container having a chamber, a sloping base in the chamber adapted to reciprocate in the direction of its slope, means 50 to guide the movement of the base, a slide in the container, and a bowed spring carried by the slide for striking the lower edge of the base and acting to shift it diagonally upwards.

In witness whereof I have hereunto set my hand.

WILLIAM SYLVESTER NEWMAN.
